DESIGN FOR A JACKET

Jacob A. Silverman, New York, N. Y.

Application November 13, 1936, Serial No. 65,873

Term of patent 3½ years

To all whom it may concern:

Be it known that I, Jacob A. Silverman, a citizen of the United States of America, residing in Manhattan, county of New York, and State of New York, have invented a new, original, and ornamental Design for a Jacket, of which the following is a specification, reference being had to the accompanying drawing, forming part thereof, wherein,

My jacket is characterized by the double pockets as shown, which pockets contrast in color, the under pocket matching the contrasting lapels and collar of the jacket as shown, and are outlined by contrasting stitching.

I claim:

The ornamental design for a jacket, substantially as shown and described.

JACOB A. SILVERMAN.
